HANDBAG

Daniel W. Wiggin, Boston, Mass., assignor to Leather Products, Inc., Boston, Mass., a corporation of Massachusetts

Application January 19, 1951, Serial No. 13,870

Term of patent 3½ years

(Cl. D87—3)

To all whom it may concern:

Be it known that I, Daniel W. Wiggin, a citizen of the United States of America, residing at Boston, in the county of Suffolk, and Commonwealth of Massachusetts, have invented a new, original, and ornamental Design for a Handbag, of which the following is a specification, reference being had to the accompanying drawing, forming part thereof.

Figure 3 is a rear elevation of the handbag with a portion of the handle omitted for convenience of illustration.

I claim:

The ornamental design for a handbag, as shown.

DANIEL W. WIGGIN.
